BAFFLE FOR BOILER TUBES

Stanley J. Clark, New Hartford, Conn., assignor
to Acme Tank & Welding Co., a Division of
United Tool & Die Company, Hartford, Conn.

Application February 19, 1948, Serial No. 9,572

7 Claims. (Cl. 110—97)

1

This invention relates to baffles for boiler tubes and more particularly to a device which is used for retarding the flow of heat through a heat exchange tube so as to increase the efficiency of the boiler.

An object of the invention is to provide such a baffle which is particularly adapted for boilers having a plurality of fire tubes extending through a water chamber.

A still further object of the invention is to provide a baffle which will retard the flow of heat through the fire tube and at the same time direct a portion of said flow into contact with the walls of the tube so as to increase the efficiency of the boiler.

A still further object of the invention is the provision of a baffle which will retard the flow of heat and which will thereby become super-heated so as to accelerate the transfer of heat through said tubes.

Further objects and advantages of the invention will be more clearly understood from the following description and from the accompanying drawings, in which—

Fig. 1 is an elevational view of a portion of a boiler including a pair of fire tubes.

Fig. 2 is a side view in central vertical section through said tubes.

As shown in the drawings, the numerals 5—6 denote, respectively, the top and lower plates of a water chamber in a boiler of conventional construction, such as includes a plurality of fire tubes 7—8 which extend vertically through the water chamber and parallel to each other.

This invention is directed particularly to the provision of a baffle which will retard the flow of heat through said tubes and direct said flow along the walls of the tubes so as to increase the transfer of heat from said tubes to the water in the water chamber.

My invention provides a baffle in the form of a tube which is preferably constructed of sheet metal of a suitable alloy to withstand high temperatures. The said tube 9 is provided with a cap, or top plate, 10 in the form of a disk extending and spaced from the top of the tube 9 and having the bottom surface thereof convex so as to direct the heat radially through the space 11 which is provided between the top edge of the tube 9 and the bottom surface of said disk 10.

The said disk may be secured to the tube by means of ears 12 which are bent downwardly from the disk and spot-welded to the tube so as to support the disk in spaced position from the

2

end of the tube. The said disk is also provided with radially projecting tabs 13 which serve to center the baffle within the tube and retain it in position wherein the walls of the baffle tube are spaced from the heat transfer tube to allow a heat passage therebetween. The bottom portion of the tube is provided with outwardly extending tabs 14 which cooperate with the tabs 13 to keep the baffle tube aligned within the fire tube.

In order to support my improved baffles within the fire tubes, there is provided a U-shaped wire hanger which has depending side portions 15—15, that are co-axial with and secured to the disk 10, and a cross bar 16 which overlies the ends of a pair of fire tubes and thereby suspends a pair of baffle tubes therein, as clearly illustrated in Fig. 2.

The said U-shaped wire member provides a 20 practical and economical means for supporting the baffles within the fire tubes, since the said baffles may be simply mounted in pairs on said U-shaped member and dropped in position within the fire tubes wherein they will be supported by the U-shaped member resting upon the top edges of said fire tubes.

In the operation of my improved baffle, the heat which is indicated by the arrows in Fig. 2, will travel upwardly in the annular space between the 30 baffle tube 9 and the fire tube 8 and also into the said baffle tube. Upon entering the baffle tube the flow of said heat will be retarded therein by the disk 9 and a restricted flow is permitted through the space 11. Retarding the flow of heat in this manner will serve to super-heat the tube 9 so that it will in turn super-heat the heated air flowing between the said baffle tube and the wall of the tube 8 and thereby accelerate the transfer of the heat to the water in the boiler and increase the efficiency of the boiler.

It has been found by actual use that the baffle tubes 9 will increase the efficiency of the boiler, when the heat is retarded within said tubes by the disks 10, since this permits the tubes to act 45 as baffles, which will direct a substantial portion of the heat flow into contact with the inner surfaces of the walls of the tubes 8, and the remaining portions of said heat flow to build up within the baffle tubes 9, due to the restricted flow permitted through the space 11, and serve to super-heat the said baffle tubes so as to in turn increase the heat transfer through the fire tubes.

I claim:

1. For a fire tube of a boiler, a baffle including 55 a tubular member smaller than the inside of said

fire tube and adapted to be positioned within the said fire tube, and a plate extending across an end of said tubular member and spaced therefrom to retard the flow of heat through said tubular member and thereby increase the heating thereof by said flow and direct a portion of said flow between the tubular member and the inner wall of the fire tube, the said plate being separate from the tube and having tabs bent downwardly therefrom and secured to the tube for supporting it, and other tabs extending outwardly from said plate, substantially on the plane thereof, for spacing the baffle from the walls of the fire tube.

2. For a vertically disposed fire tube of a boiler, a baffle comprising a tubular member of lesser outside diameter than the inside diameter of the fire tube and adapted to be supported within said fire tube co-axially therewith, a disk-shaped member extending across and spaced from the upper end of said tubular member and secured thereto by means of spaced tabs bent downwardly from said disk-shaped member, and radially extending tabs on said disk-shaped member for centering the said tubular member within the fire tube.

3. For a fire tube of a boiler, a baffle including a vertically disposed tubular member of lesser outside diameter than the inside diameter of the fire tube, a disk-shaped member secured to and extending transversely of said tubular member and spaced from the top thereof to retard the flow of heat to said tubular member; the lower surface of said disk-shaped plate being convex to direct the heat flow towards the space between said plate and the upper edge of the tubular member, tabs radiating from said plate and from the lower portion of said tubular member for centering the said baffle within the fire tube, and means for supporting the said baffle within the fire tube.

4. For the fire tube of a boiler, a baffle including a tubular member of lesser outside diameter than the inside diameter of the fire tube, means for retarding the flow of heat through said tubular member, and means for supporting said tubular member within the fire tube and longitudinally thereof including an integral inverted U-shaped wire hanger extending secured to said tubular member and adapted to extend into the fire tube over the edge thereof and into an adjacent fire tube for supporting a similar baffle therein.

5. For a boiler including a plurality of vertically extending fire tubes, a heat flow baffle including a plurality of tubular members having means for retarding the flow of heat therethrough and being of a lesser outside diameter than the inside diameter of said fire tubes, and an integral inverted U-shaped supporting member having said tubular members suspended from the ends thereof and being adapted to extend over the upper ends of two adjacent fire tubes for supporting one of said tubular members longitudinally in each of the fire tubes.

6. For a fire tube of a boiler, a baffle device including an integral inverted U-shaped wire hanger, a disk-shaped member secured to the end of each leg of said hanger on a plane perpendicular to the sides thereof, and a tubular member suspended perpendicularly from each of said disk-shaped members and spaced therefrom; the said hanger being adapted to extend over the top edges of two adjacent fire tubes and support said baffle tubes therein and co-axially therewith.

7. For a boiler having a plurality of justaposed vertically extending fire tubes, a baffle device including a pair of baffles each comprising a disk-shaped plate, a tube suspended perpendicularly to and spaced from said plate, a plurality of tabs radiating from said disk-shaped plate and tubular member for centering them within the fire tubes, and an integral inverted U-shaped wire hanger connected to said pair of baffles and adapted to extend over the top edges of the two adjacent fire tubes and support one of said baffles in each of said fire tubes.
